J. Nicol,

Die for Forming Axles.

NO. 98878.

Patented Jan. 18, 1890.

United States Patent Office.

JOSEPH NICOL, OF AUBURN, NEW YORK, ASSIGNOR TO SHELDON & CO.

Letters Patent No. 98,878, dated January 18, 1870.

IMPROVED SERIES OF DIES FOR FORMING AXLES.

The Schedule referred to in these Letters Patent and making part of the same.

To all whom it may concern:

Be it known that I, JOSEPH NICOL, of the city of Auburn, in Cayuga county, New York, have invented a new and useful Improvement in Swaging Axles, and drawing out and forming the arm, swell, and collar, at one heat, whereby I am enabled to save much time, and produce better work than by any other process known to me, and requiring two heats.

The invention consists in dies, formed as hereinafter more fully described.

Figure 1 represents the lower, and

Figure 2, the upper portion of my improved dies.

Figure 3 shows the form given to a piece of round iron or steel by dies No. 1.

Figure 4 shows the form in which the iron is left after being operated upon by dies No. 2.

Figure 5 represents the work finished by dies No. 3.

Heretofore, in the manufacturing of axles, the dies have been so shaped as to bear equally upon the whole portion of the metal under them, thereby requiring more time to swage the blank to the proper form for an axle, and during such time the iron gradually cools, rendering it necessary to reheat it before the axle can be fully formed.

It is well known that the iron, when at white heat, and first placed in the die, is in the best condition to be swaged into the form required, and at that time less power is required to force the iron into a die or form.

The die No. 1 is specially constructed, so that nearly the whole force of the blow of the hammer or drop is exerted on that portion of the iron to form the collar B and the square C back of it, the forward portion of the die being made of conical form, to allow the iron, in advance of the collar, which is to form the swell E and arm F, to spread out freely.

By distributing the force of the hammer at this point, in relation to the die and axle, I am able to form more expeditiously the collar and square.

When the iron has been swaged, by die No. 1, to the form represented in fig. 3, it is then laid quickly in die No. 2, with the collar B against the side, i, of the die, and is turned by the operator in the usual man-

ner. The portion of the die marked e, forms the swell E, and that portion marked f, forms the arm F; but the portion f does not, owing to the construction of the die, commence to operate on the iron until the collar is about finished, and then it operates gradually, to form the required taper, the conical portion, f, of the die gradually drawing the part D to the size required to adapt it to enter between the portions f of the die, where it is further reduced.

When the iron is removed from die No. 2, it has the form represented in fig. 4, then it is placed in die No. 3, and the arm, swell, and collar are finished and formed to the required shape, and as shown in fig. 5.

The parts c b d, of die No. 1, form the iron into the shape C B D.

The iron, when first heated and operated on, is in bar-form, and it is inserted in die No. 1, until its end rests against the gauge A, which is regulated according to the length of the arm required.

By the gradual reduction of the iron, and concentrating the force of the hammer upon only portions of the material within the die when in its most heated condition, and as described, I am enabled to produce, as I believe, for the first time, by one heat, an axle, having an arm, swell, collar, and square, ready for trimming.

Before the arm is turned in the lathe, that portion back of the collar B is drawn down to the proper square, in the usual manner, and cut off.

The lower die rests on an anvil, or firm foundation, and the upper die is to be operated in any known way, by suitable trip or steam-hammer.

Claim.

I claim the series of dies, constructed as described, and operating gradually on the iron, to form the square, collar, swell, and arm, in the manner substantially as set forth.

JOSEPH NICOL.
